LAMP SHADE

William T. Partridge, Washington, D. C.

Application May 25, 1932, Serial No. 613,511

10 Claims. (Cl. 240—108)

The present invention relates to a lamp shade and more particularly, a lamp shade which may be readily arranged to provide a number of different ornamental effects.

5 Lamp shades of present day manufacture usually have a single surface with a fixed design applied thereto which cannot be changed by the purchaser to suit his individual tastes or requirements. Very often it becomes desirable to 10 slightly change the color of the lighting effects in a room, particularly when some change is made in the arrangement of the other furnishings of the room, and in order to completely accomplish this result, it is usually necessary to purchase 15 new lamp shades. Also, lamp shades having a fixed design thereon do not generally harmonize with the furnishings of different rooms and, therefore, may not be moved from the room for which they were particularly purchased.

20 The principal object of my invention is to provide a lamp shade which will produce a number of distinctly unusual and novel lighting effects.

A further object of my invention is to provide 25 a lamp shade which may be readily changed to harmonize with different settings.

Another object of the invention is to provide 30 a lamp shade which may be varied to produce different designs and which can be made from a previously formulated general design and color scheme by one not necessarily highly skilled in the decorative arts.

Still another object of the invention is to provide 35 a lamp shade formed of units which may be interchangeably assembled by the purchaser to provide a design and color to suit his particular tastes.

In the drawing,

Figure 1 is a side elevation of a lamp provided 40 with a lamp shade of my invention, with a portion of the lamp shade broken away;

Figure 2 is a central vertical section through a portion of the lamp shade;

Figure 3 is a horizontal section of the lamp shade shown in Figures 1 and 2;

45 Figure 4 is a horizontal section through a modified form of my lamp shade;

Figure 5 is a vertical section through a modified form of my lamp shade, taken on the line 5—5 of Figure 6; and

50 Figure 6 is fragmentary side elevation of the lamp shade illustrated in Figure 5.

Referring to the form of my invention illustrated in Figures 1, 2, and 3, the numeral 10 designates a lamp base of any well known type 55 which supports a lamp bulb 11 at its upper end,

the lamp bulb preferably having the usual substantially circular and horizontally disposed filament therein as indicated at 12. A lamp shade support 13 is secured upon the lamp bulb 11, but it will be understood that a lamp shade support of any suitable type may be substituted therefor.

5 The lamp shade comprises inner and outer members 14 and 15 respectively, each of which preferably has the form of a truncated cone. The 10 wall of the outer member 15 is less sharply conical or angled with respect to a vertical line than the wall of the inner member 14 and is provided with vertically extending plaits or corrugations 16 of any desired cross-section, the depth of these 15 plaits increasing from the upper portion 17 of the outer member 15 to the lower portion 18 thereof. The inner member 14 may be formed of any transparent material which has sufficient 20 rigidity, but I find it desirable to form this member from a transparent sheet material which can be bent or formed to the desired shape. The outer member 15 is preferably formed of a translucent material, the type of parchment paper generally used for lamp shades being particularly 25 suited for this purpose. The outer member 15 is supported upon the inner member 14, the inner apices 19 of the plaits 16 resting directly upon the outer surface of the inner member 14.

30 In order to create a design upon the outer member 15, I preferably apply transparent coloring materials over varying areas of the inner surface of the member 14. A number of such design areas are indicated on the drawing by the numerals 20, 21, 22, and 23. It will be understood that these 35 areas may be positioned upon any portion of the surface of the inner member 14 but the areas diagrammatically illustrated on the drawing will serve to illustrate the design effect which may be obtained by the use of my lamp shade. The 40 upper design areas 20 and 21, being closely adjacent the lamp filament 12, will cause very slightly enlarged projected design areas 24 and 25, respectively, to appear upon the outer member 15, these projected areas 24 and 25 also being only 45 slightly larger than the original design areas 20 and 21 because of the fact that the members 14 and 15 are relatively close together at this point. The fact that the design areas 20 and 21 are substantially at right angles to the path of the light 50 rays will cause the edges of the projected design areas 24 and 25 to be sharp and distinct. The design areas 22 and 23 being more distant from the lamp filament 12 and being arranged at a sharper angle with respect to the path of the light 55

rays emanating from the filament, will cause relatively larger projected areas 26 and 27 to appear upon the surface of the outer member 15. When, as is preferable, a lamp bulb having a substantially circular and horizontally disposed filament 12 is used, a penumbra effect 28 will appear at the edges of the projected design areas 26 and 27, causing these areas to be increasingly softened and producing unexpected and artistic effects.

10 The outer member 15 being plaited, the designs projected thereon will be enlarged in a horizontal plane as shown in Figure 3 and will appear at various angles with respect to the horizontal and this effect, together with the effect resulting from 15 the difference in the conical inclinations of the surfaces 14 and 15, will cause the entire design projected upon the outer member 15 to have characteristics entirely different from that of the design which is applied to the inner member 14 and 20 very simple design areas upon the inner member 14 will cause unusual and unique designs to be projected upon the member 15. The design applied to individual inner members 14 need not be executed with a great amount of care, although, 25 it is, of course, important to have the design areas, and particularly the color schemes, used for a group of generally similar lamp shades, formulated by one skilled in design work.

Figure 4 illustrates a modification of my invention 30 wherein two inner members 29 and 30 are provided for use with a plaited outer member 31. Each of the inner members 29 and 30 bears a design area of the type described in connection with the inner member 14 of Figures 1 to 3, inclusive. The design areas 32 upon the member 29 and the design areas 33 upon the member 30 are preferably of different outlines and have different colorings. The members 29 and 30 are 35 preferably arranged so that they may be positioned in any desired manner with respect to each other. Since the corresponding design areas 32 and 33 upon the inner members 29 and 30 will have different color schemes and/or will be of different shapes and sizes, the light rays passing therethrough will be vari-colored and different 40 arrangements of the inner members 29 and 30 with respect to each other will cause changes in the color and shape of the projected design areas upon the outer member 31.

Figures 5 and 6 of the drawing illustrate another modification of my invention wherein the plaitings are omitted from the outer member. In the device of Figures 5 and 6, I preferably apply a suitable illustrative design to the interior of the inner member 34, and the shadow of this design 55 is projected upon the outer member 35. As illustrated in Figure 5, the design shows a ship upon a body of water. The illustration of the ship being upon the upper portion of the inner member 34, the shadow 36 thereof will be cast upon the upper portion 37 of the outer member 35 and since this portion of the outer member 35 is relatively close to the upper portion of the inner member 34, the image 36 will have a clear and distinct outline for the reasons stated in connection with the Figure 1 form of the invention. However, the remainder of the original design, i. e., the shadow of the ship and the lines indicating a body of water, will be projected upon the lower portion of the outer member 35. Since this portion is more widely spaced from the inner member 34 and since the light rays casting this shadow act at a sharper angle, the resulting image 38 thereof projected on the outer member 35 will be in the form of soft shadows having indistinctly 70

defined edges. This effect will be heightened when a parchment having a softly mottled texture is used for the outer member 35.

It will be understood that color effects may be used with the form of my lamp shade shown in Figures 5 and 6 as well as in the forms shown in Figures 1 to 4.

While a transparent material is preferred for use in the inner member or members of my lamp shade, translucent materials may be used. It will 10 also be understood that the lamp shade members need not be frusto-conical.

I claim:

1. A lamp shade comprising an inner transparent member bearing a design thereon and a 15 corrugated member surrounding the first member and serving as a screen upon which the design of the inner member is projected.

2. A lamp shade comprising an inner transparent member bearing a design thereon and a 20 corrugated translucent member surrounding and spaced from the inner member and serving as a screen upon which the design of the inner member is projected.

3. A lamp shade adapted to be used with a 25 source of light, said lamp shade comprising an inner member bearing a design thereon and an outer member serving as a screen upon which the design of the inner member may be projected, said members being arranged in a plane 30 non-parallel to the axis of the source of light and at an angle with respect to each other.

4. A lamp shade adapted to be used with a 35 source of light, said lamp shade comprising an inner circular member bearing a design thereon and an outer circular member serving as a screen upon which the design of the inner member may be projected, said members being arranged in a plane non-parallel to the axis of the source and at an angle with respect to each other.

5. A lamp shade adapted to be used with a 40 source of light, said lamp shade comprising an inner member bearing a design thereon and an outer member serving as a screen upon which the design of the inner member may be projected, one of said members being corrugated.

6. A lamp shade adapted to be used with a 45 source of light, said lamp shade comprising an inner member bearing a design thereon and an outer member serving as a screen upon which the design of the inner member may be projected, the outer member being corrugated.

7. A lamp shade adapted to be used with a 50 source of light, said lamp shade comprising an inner member surrounding the source of light and bearing a design thereon and an outer circular member surrounding the first member and serving as a screen upon which the design of the inner member may be projected, one of said members being corrugated.

8. A lamp shade adapted to be used with a 55 source of light, said lamp shade comprising an inner circular member surrounding the source of light and bearing a design thereon and an outer circular member surrounding the first member and serving as a screen upon which the design of the inner member may be projected, the outer member being corrugated.

9. A lamp shade adapted to be used with a 60 source of light, said lamp shade comprising an inner circular member bearing a design thereon and an outer circular member serving as a screen upon which the design of the inner member may be projected, said members being arranged in a 65

plane non-parallel to the axis of the source of light and at an angle with respect to each other, one of said members being corrugated.

10. A lamp shade adapted to be used with a source of light, said lamp shade comprising an inner circular member bearing a design thereon and an outer circular member serving as a screen

upon which the design of the inner member may be projected, said members being arranged in a plane non-parallel to the axis of the source of light and at an angle with respect to each other, one of said members being corrugated. 5

WILLIAM T. PARTRIDGE.
